UNITED STATES PATENT OFFICE

98,308

DESIGN FOR A DOME LIGHT

Burton S. Floraday, Toledo, Ohio, assignor to
Dura Company, Toledo, Ohio, a corporation of
Ohio

Application August 23, 1935, Serial No. 58,255

Term of patent 7 years

To all whom it may concern:

Be it known that I, Burton S. Floraday, a citizen of the United States and resident of the city of Toledo, county of Lucas, State of Ohio, have invented a new, original, and ornamental Design for a Dome Light, of which the following is a specification, reference being had to the accompanying drawing, forming a part thereof.

In the drawing—

Figure 1 is a top plan view of the dome light; and

Figure 2 is an edge view of the dome light, a portion being broken away showing the manner in which the peripheral edge of the lens overlies a portion of the rim.

The dominant feature of my design resides in

a dome light comprising a casing and a lens, in which the casing is provided with an upwardly and inwardly extending curved rim, the lens being dome-shaped and provided with a flange fitting in the rim of the casing; the curvature of the lens merging into the outline of the rim, and the lens being further provided with an outwardly extending flanged edge overlying and covering the adjacent portion of the rim.

I claim:

The ornamental design for a dome light, as shown and described.

In testimony whereof I have hereunto signed my name to this specification.

BURTON S. FLORADAY.
